UNITED STATES PATENT OFFICE.

ALEXANDER McNAB, OF BRIDGEPORT, CONNECTICUT.

SOUND-LOCATING DEVICE.

Application filed January 21, 1920. Serial No. 352,981.

To all whom it may concern:

Be it known that I, ALEXANDER McNAB, a subject of the King of Great Britain, residing at Bridgeport, in the county of Fairfield and State of Connecticut, have invented certain new and useful Improvements in Sound-Locating Devices, of which the following is a specification.

This invention pertains to sound locating devices and relates more particularly to an instrument for detecting the point from which a sound emanates. The instrument while designed more particularly for locating the origin of sounds in machinery is, in its broader concept, applicable for medical research inasmuch as it is extremely sensitive and may be advantageously employed in lieu of the stethoscopes now commonly used.

20 The structure is illustrated in the annexed drawings, wherein,—

Fig. 1 is a diagrammatic elevation of the instrument in its complete form;

25 Fig. 2 a longitudinal sectional view, with parts in elevation, of the hand piece carrying the make and break device adapted to be brought into action or functioning relation by a pressure producing element which latter is forced against or held in contact with the machine (or other body) from which the sound to be located emanates;

30 Fig. 3 an enlarged sectional view thereof; and

Fig. 4 a sectional view showing a slight modification or adaptation of the structure.

Referring first to Figs. 1 to 3, 1 denotes a suitable box or case in which is fixed two spring terminals 2 and 3 between which is placed a dry cell or battery 4. An induction coil 5 is also located within the box, the secondary winding whereof is connected by leads 6 and 7 with the ear piece 8 of any approved type of head set, indicated generally by 9. A lead 10 extends from terminal 2 to one terminal of the primary winding of the induction coil and a lead 11 extends from the opposite terminal of the primary winding to a socket terminal 12 mounted in the head 13 of the hand piece, the main body whereof is designated by 14. A lead 15 extends from the terminal 3 to a second socket terminal 16 mounted in head 13. The body 14 is preferably formed of a suitable dielectric material as gutta-percha and carries a pair of metal pins or posts 17 and 18 pref-

erably split at their outer ends to produce a close contact with the wall of the respective sockets 12 and 16 into which the pins extend. Pin 17 is connected through a wire 19 with a metallic sleeve or bushing 20 fixedly secured in the forward portion of a socket or recess 21 formed in the rear portion of the body 14. Said sleeve is internally threaded and a screw 22 is mounted therein, the head of the screw being housed within the recess 21, while its forward end extends into a bore which passes longitudinally through the body member 14.

Located within the bore in advance of and in contact with the screw is a disk 23 formed of carbon or platinum, said disk in turn bearing against a body of carbon 24, said body being somewhat loosely confined between disk 23 and a similar disk 25. Extending forwardly from the latter is a plunger pin 26; a spring 27 is interposed between said pin and a second pin or rod 28. In other words, the pins 26 and 28 and the intermediate spring form a yielding pressure device which exerts a compressive force upon the variable resistance element 24.

The outer end of the body 14 is reduced in diameter somewhat and a cap piece 29 is screwed thereon, said cap confining a felt nose piece or button 30 which forms the guide or support for a finger 31, said finger carrying at its inner end a head 32 which bears against the forward end of rod 28. The finger 31 is designed to be pressed against the body from which the sound to be located emanates, as for instance, a cylinder head 33, Fig. 1, and to transmit the sound waves or vibrations through the rods 26, 28 and spring 27 to the variable resistance element 24. Said rods are housed within and in contact with a metallic sleeve or bushing 34 secured within the body 14 and said sleeve is connected with the pin 18 through a wire 35 embedded in the body. To maintain the parts in their proper working relation, the screw 22, when once brought to such position that the variable resistance element will be held under the requisite degree of compression when the finger 31 is forced inwardly, will be secured in place as by pouring a body of sealing wax 36 in the cavity 21, the wax, when it becomes hard, preventing the screw from turning in either direction. The instrument may be readily adjusted. Placing the finger 31 against a body

from which a known sound emanates, and with the head piece 9 in place, one may readily determine whether the element is under the proper degree of compression. By removing the cap 13 access is had to the screw which is turned in or out and the cap replaced reestablishing the circuit connections. When the screw is finally brought to its proper position it is secured in any suitable way, as by wax, as above indicated, and the cap replaced.

In Fig. 4 a modification of the invention is illustrated, certain features of which may be incorporated in the form just described. Under this arrangement it will be noted that the screw 22 extends outwardly through an opening formed in the head 13 and is provided with a milled head 22^a by which it may be adjusted. This permits manual adjustment of the screw, if for any reason a greater or less pressure is desired upon the variable resistance. So also instead of employing a straight rounded finger the finger designated by 31^a carries at its outer end a cupped shaped element, as 37, thereby adapting the instrument to stethoscopic purposes. When so employed it may be found necessary to vary the resistance and by the utilization of the milled head 22^a this may be readily effected.

From the foregoing it is thought that the operation and utilization of the instrument will be readily appreciated. The various parts which are not permanently attached to

the box may be readily housed therein and thus a simple portable apparatus provided.

What is claimed is:

1. In a microphone for use in sound locating devices the combination of a body; a resistance mounted therein and adapted to be included in a circuit with the primary windings of a coil; a plunger extending forwardly from the resistance; a spring bearing against the forward end of the plunger; a second plunger mounted in the body and bearing on the opposite end of the spring; a cap piece mounted on the outer end of the body; a felt nose piece mounted in the cap; and a finger guided and supported by the nose piece, said finger at its inner end bearing against the second named rod.

2. In a microphone for use in sound locating devices the combination of a body; a variable resistance element mounted in the body and adapted to be included in the circuit of the primary windings of a coil; a yielding pressure device located in the body and exerting a compressive force upon the variable resistance; a soft nose piece carried by the body in line with the yielding pressure device; and a finger extending through said nose piece being guided and supported thereby, said finger at its inner end contacting upon the yielding pressure device.

In testimony whereof I have signed my name to this specification.

ALEXANDER McNAB.
